UNITED STATES PATENT OFFICE.

ABRAHAM KNISELY, OF CHICAGO, ILLINOIS.

METALLIC LATHING.

SPECIFICATION forming part of Letters Patent No. 252,679, dated January 24, 1882.

Application filed October 13, 1881. (No model.)

To all whom it may concern:

Be it known that I, ABRAHAM KNISELY, residing at Chicago, in the county of Cook and State of Illinois, and a citizen of the United States, have invented a new and useful Improvement in Metallic Lathing, of which the following is a full description, reference being had to the accompanying drawings, in which—

Figure 1 is a vertical cross-section of a portion of a ceiling, showing two beams or girders, a furring or angle iron, metallic lathing, and the devices or means for attaching the lathing and furring or angle iron; Fig. 2, a horizontal section on line xx of Fig. 1, looking down on the lathing; Fig. 3, a transverse vertical section on line yy of Fig. 1; Fig. 4, an enlarged detail, being a side elevation of the girder or beam clamp, receiving or supporting plate, and furring or angle iron; Fig. 5, a top or plan view of the parts shown in Fig. 4; Fig. 6, an enlarged detail, being an end elevation of one section of the beam-clamp, the receiving or supporting plate, and furring or angle iron; Figs. 7 and 8, enlarged details, being a side and edge elevation, respectively, of the receiving or supporting plate.

This invention relates to means or devices for attaching the furring or angle irons to which metal lathing is secured to the girders or beams, and the attachment of the metal lathing to the furring or angle iron, and has for its object to secure the furring or angle irons in proper position readily and quickly, without any waste of time or labor in adjusting, marking, and fitting the same, and to attach the lath in any efficient and reliable manner to the furring or angle irons; and its nature consists in providing a divided clamp to fit the girders or beams, and adapted to receive the furring or angle irons and retain the same in position on the girders or beams; in providing a divided clamp to fit the girders or beams, and a supporting or retaining piece located between the sections of the clamp and adapted to receive the angle-iron and retain it in position to be secured to the girders or beams by the clamp; in providing the lath-attaching flange of the angle-iron with openings for the passage of fastening-wires, and providing fastening-wires passing under the lathing and over the flange of the furring, through the openings

in the furring, to form a continuous binding, by which the lathing is secured in position; and in the several parts and combination of parts hereinafter set forth as new.

In the drawings, A represents the girders or beams. B B' represent the sections of the clamp; C, the furring or angle iron support; D, the furring or angle iron; E, the metal lathing; a, the flange of the girders or beams; b, the clamp-openings to receive flange a; b', the depending ends for attaching the clamp-section together; c, the opening in C for the furring or angle iron; c', the tightening or clamping bolt; d, the openings in the flange of D for the passage of the wires; e, the binding or fastening wires; f, the openings for inserting bolts or rivets through the clamp and furring.

The girders or beams A may be made of cast-iron or other suitable material, as usual, and may be of the form shown, or of any other desired form, with a flange, a, to which the clamp can be attached, which flange may be of the form shown or other suitable forms.

The sections B B', forming the clamp, may be made of malleable iron or other suitable material that can be cast or otherwise formed into shape. As shown, each section has a body or main portion, at one end of which is a depending lip or end flange, b', having an opening through which a bolt or rivet, c', passes, by means of which the two sections, when in place on the girder, are held together and in position so as not to slip or yield. The other end of each section is provided with an upturned ear or flange of such form as to leave an opening, b, to receive the flange a of the girder or beam, the shape of the opening b and of the flange a corresponding.

The supporting-plate C may also be made of malleable iron or other suitable material, and may be formed as shown, or of some other suitable form, having an opening, e, which, when the parts are together or in place, stands clear of the side of the clamp to receive the furring-strip or angle-iron and furnish a support therefor and allow the plate to slide thereon. This plate is located between the depending lips b' of the clamp-sections, and is locked and held in position by the same clamping bolt or rivet, c', which secures the sections together.

The opening *c* corresponds in shape to the shape of the angle-iron, but, as shown, is somewhat larger than the thickness and width of the iron, in order to allow the plate *C* to slide 5 easily in adjusting the clamp to the position of the girder or beam, and, as shown, the plate *C* has ledges or ribs on its side, against which the ends of the ears *b'* come in contact when the parts are together, and form a bearing 10 to which prevents the plate or the clamp-sections from turning on the bolt or rivet, and causes one part to support the other.

The furring or angle iron *D* may be of the form shown, or of any other suitable form, with 15 the flange or portion against which the lathing is in contact provided with openings for the passage of the binding-wires *e*. These openings *d* may be of the form shown, with a mouth or opening leading to the edge of the 20 flange, or they may be of any other form adapted to pass the wire alternately over the flange and under the lathing, between the opening, to form a continuous bind.

The lathing *E* may be of the form shown, or 25 any other form under which wires can be passed to attach it to the furring or angle iron.

The clamp *B B'* can be used for attaching furring or angle irons to be used with other means than the binding-wires *e* for attaching 30 the lathing, and this clamp can also be used without the plate *C*, in which case the side web of the body of each section is to be provided with an opening, *f*, through which and the angle-iron a suitable bolt or rivet can be 35 passed to secure the angle-iron to the clamp.

In use, to attach the furring or angle iron to the girders or beams when the plate *C* is used, as many of such plates as there are girders or beams to be attached to are slipped onto 40 the angle-iron, and the attachment is completed as follows: A plate, *C*, with a section of the clamp, is moved on the iron until the desired position is reached beneath a girder; then the section of the clamp is slipped onto that side 45 of the girder, the flange *a* entering the opening *b*; then the other section of the clamp is slipped onto the opposite side of the girder in the same manner, and the bolt or rivet *c'* inserted and brought to place, locking the beam, 50 sections, and plate together, and securing the same with the angle-iron to the beam or girder, and this operation is repeated for each plate until all the plates *C* are attached. By this arrangement it will be seen that the furring or 55 angle iron can be readily and quickly and easily placed and secured in position without requiring any great amount of skill in fitting and arranging the parts, as all that is necessary to be done is to place as many plates *C* 60 on the angle-iron as there are girders to be attached, move these plates along as required to bring one in position for each girder, slip the clamp-sections onto the girder, one on each side, with the plate *C* between them, and then 65 secure the whole together by a bolt or rivet.

When the plate *C* is not used the sections of the clamp are placed in position on the

girder or beam, and the angle-iron placed in position and holes drilled or made therein to coincide with the holes *f*, so as to pass a bolt 70 or rivet through each clamp-section and the angle-iron, securing the angle-iron to the clamp, with the clamp attached to the girder or beam.

The lathing is secured in place by the binding-wires *e*, which pass transversely under the 75 lathing and longitudinally over the flange of the angle-iron. Two of these wires *e* are used, passing alternately under the lath and over the flange between the openings *d*, in such manner that a binding will be furnished for 80 all the laths, each wire furnishing the fastenings or bindings for alternate laths, one wire passing under a lath, thence up through a hole, *d*, over the flange of the angle-iron to the next hole *d*, thence down through that hole 85 and under the lath, and then up through a hole *d*, and over the flange again, and so on to the end, and the other wire passing over the flange where the first wire passes under the lathing, and under the lathing where the 90 first wire passes over the flange from end to end of the furring, so as to produce in connection with the first wire a continuous binding, by which the lathing will be held securely in place. 95

By the use of this method of fastening no projecting surfaces are left, as where bolts or rivets are used, producing a better and more uniform surface to receive the plaster than where bolts or rivets are used, and at the same 100 time the wires can be very easily and readily applied.

What I claim as new, and desire to secure by Letters Patent, is as follows:

1. A divided clamp consisting of two sections, *B B'*, adapted to receive and support the furring or angle iron, and to be attached to the girder or beams to furnish a support for metallic lathing, substantially as specified. 105

2. A divided clamp consisting of two sections, *B B'*, adapted to be attached to the girders or beams, in combination with a plate or support, *C*, for the furring or angle iron, for securing the furring or angle iron in position, substantially as and for the purposes specified. 110

3. The binding-wires *e*, in combination with the furring or angle iron *D*, having openings for the passage of the wire *e*, and metallic lathing *E*, for attaching the lathing to the furring or angle iron by winding the wires under the lathing and over the furring, substantially as specified. 115

4. A divided clamp consisting of two sections, *B B'*, and a plate or support, *C*, in combination with the furring or angle iron *D*, having openings for the passage of wire, metallic lathing *E*, and binding-wires *e*, for securing metallic lathing to girders or beams, substantially as specified. 120

ABRAHAM KNISELY.
